Primary Examiner—Louis S Zarfas*Assistant Examiner*—Michelle E Wilson(74) *Attorney, Agent, or Firm*—St. Onge Steward Johnston & Reens LLC(57) **CLAIM**

The ornamental design for sanitary napkin, as shown and described.

DESCRIPTION

FIG. 1 is a front perspective view of a sanitary napkin in accordance with the new design;

FIG. 2 is a top view thereof;

FIG. 3 is a side view thereof;

FIG. 4 is an end view thereof; and,

FIG. 5 is a bottom view thereof.

The broken lines shown in the drawings are for illustrative purposes only and form no part of the claimed design.
